UNITED STATES PATENT OFFICE.

ROBERT ZAHN, OF PLAUE, GERMANY.

JACQUARD-CARD-PUNCHING MACHINE.

965,056.

Specification of Letters Patent. Patented July 19, 1910.

Application filed March 18, 1910. Serial No. 550,179.

To all whom it may concern:

Be it known that I, ROBERT ZAHN, a subject of the King of Bavaria, and resident of Plauen, Germany, engineer, have invented new and useful Improvements in Jacquard-Card-Punching Machines, of which the following is a full, clear, and exact specification.

The cards used in working a jacquard embroidery machine are perforated, as is well known, with holes in accordance with the length of the various stitches, in a so called card punching machine, whereby the separate stitches are decomposed into components in two given directions by means of a cross-slide and are transmitted in each component direction to the card punching mechanism by means of a particular punch selecting device. The most important part of such a selecting device is an adjustable selector designed to be adjusted according to the length of the stitches and which consists of pin wheels or pin drums, in the present well known machines of this kind.

The present invention relates to jacquard-card-punching machines of this kind and consists in an improved punch selecting device comprising for the stitch transmission control in one component direction a movable punch selecting member capable of being adjusted on either side of a zero position and having holes and slots constituting a pattern scale on both sides of a zero line, means to operate said punch selecting member according to the stitch length to be transmitted in the respective component direction and an automatic returning mechanism arranged to restore the punch selecting member at the end of every stitch movement, when this has operated a corresponding punch selection, positively back into its zero position.

The accompanying diagrammatic drawing shows a method of carrying out the invention and also two modifications of the punch selecting or perforation determining member.

Figure 1 shows the complete arrangement mounted on a jacquard-card-punching machine. Figs. 2 and 3 show the punch selecting or perforation determining member of this arrangement in front elevation and in plan respectively, and Figs. 4, 5 and 6, 7 show the two modifications mentioned above.

1 (Fig. 1) is the card to be perforated, which is intermittently drawn forward un-

der the punch box 3 carrying the punches 2, so as to be perforated by the said punches. The punch box 3 is adapted to be raised and lowered from time to time by means of a lever 4.

The punches 2 may be rigidly coupled in a selective manner to the punch box 3 by means of lifting bars 5 which are controlled by selecting pins 6 and may be coupled upon a driving lever 7 according to their respective positions, so that they may be shifted forward by the lever 7 to lock the punches in the punch box 3. The pins 6 are held in a vertically movable carrying piece 8 which may be moved from time to time by a lever 9. These parts belong to the particular card punching mechanism.

10 is the pattern board on which the design is fixed. The guide needle 11 is correspondingly moved over the design by the operator controlling the handle 12. In this operation the frame 13 follows each movement in the horizontal direction, that is to say, has the horizontal component of each stitch imparted to it. The rack 14 imparts the movement of the frame 13 to the pinion 15 and through the pinion 16 to the horizontal rack 17 which is connected to the perforation determining or punch selecting member 18. The latter consists of a horizontally guided reciprocating slide which is movable under the selecting pins 6 to either side of a given zero line. This slide 18 as may best be seen from Fig. 3, is provided with a pattern scale of holes and slots which is arranged symmetrically on both sides of a zero point marked by the line I, on which there is no hole or slot and which lies immediately below the row of selecting pins 6. The holes and slots on the slide forming the scale are arranged in as many longitudinal rows as there are pins 6 so that for each pin 6 there is a corresponding longitudinal scale row, and further the holes of one longitudinal hole row are longitudinally displaced relatively to the corresponding holes in the neighboring hole row by a space equal to the pitch of the teeth on the rack 17.

The perforation determining or punch selecting slide 18 is temporarily held in the adjusted position by means of a locking lever 19 which is brought into engagement at that moment with the pinion 16 by the movement of a lever 20.

In order to bring the perforation determining or punch selecting slide 18 back into

its zero position in a positive manner and very exactly, a pair of returning nipper-jaws 21 is arranged over the rack 17, which is normally open, but can be periodically closed by means of a lever 22 and link 23 upon a pin 24 on the rack 17, which stands vertically below the pivoting point of the nipper-jaws 21 in the zero position of the slide 18. It may easily be understood that 10 when the pin 24 has been moved to either side of the vertical through the pivoting point of the nipper-jaws, owing to the movement of the slide 18, it will, together with the slide 18, be positively brought back by 15 the closing of the nipper-jaws into the normal position, so that the slide 18 is again brought into its exact zero position. This returning of the perforation determining or punch selecting slide 18 only operates after 20 the rack 17 is put out of engagement with the pinion 16 by means of a disconnecting lever 25 and a rod 26.

The movements of the single levers 4, 7, 9, 20, 22 and 25 are controlled by cam 25 grooves 4^a, 7^a, 9^a, 20^a, 22^a and 25^a on a disk 28 on the shaft 27, and these cam grooves are so formed and arranged relatively one to the other, that the single movements of the levers take place at their proper times in 30 the order set forth below. The cam disk 28 turns in the direction of the arrow indicated in Fig. 1 and is so driven that it makes one revolution for every complete cycle of operations.

35 The operation of the whole arrangement is as follows: If a movement is executed on the design with the guide needle 11, so that the horizontal component of a stitch movement is imparted to the frame 13, the rack 40 17 pushes the perforation determining or punch selecting slide 18 away from its zero position to one side or the other, and the locking lever 19 is then forced into engagement with the pinion 16 by the action of the 45 cam groove 20^a on the lever 20 so that the slide 18 is held fast in its new position. Should for instance the slide 18 be thrust toward the left a distance corresponding to four consecutive teeth divisions of the 50 rack 17, then the hole α (Fig. 3) of the slide will be under the vertical row of pins 6. The pin carrying piece 8 with the pins 6 is now lowered owing to the action of the cam slot 9^a on the lever 9, whereby the pin 55 6 which happens to be opposite the hole α , enters the latter and allows the lifting bar 5 resting upon it to drop down, so that this latter is coupled upon the lever 7. The lever 7 is then swung out by the action of the cam 60 groove 7^a and thereby pushes the coupled bar 5 over the corresponding punch 2 to lock the latter in the punch box 3. Immediately afterward the punch box 3 with the punches 2 is lowered by the action of the 65 cam groove 4^a on the lever 4 and the punch

locked or coupled to it stamps out a hole in the card corresponding to the position of the slide 18. After the punch box 3 has been again raised, the card is fed forward one step by a pawl mechanism, not illustrated, while the lever 7 pulls back the coupled bar 5. The pin carrying piece 8 then returns to its upper position while the rack 17 is disengaged from the pinion 16 by the action of the cam groove 25^a on the lever 25. 70 The lever 22 is now so actuated by the cam groove 22^a that the nipper-jaws 21 are closed whereby the disengaged rack 17, and with it the perforation determining or punch selecting slide 18, is necessarily brought back 80 exactly into the initial or zero position. The nipper-jaws 21 now again open, the rack 17 is again brought into engagement with the pinion 16, and finally the locking lever 19 is brought out of engagement with this 85 pinion. The cam disk 28 has completed a full revolution during the above operations and it can again begin the cycle of operations when the perforation determining or punch selecting member is again moved. 90

In the modification according to Figs. 4 and 5, the perforation determining or punch selecting member consists of a revoluble drum 18' whose peripheral surface is provided with the same pattern of holes and 95 slots as that illustrated in Fig. 3.

According to Figs. 6 and 7 the perforation determining or punch selecting member consists of a revoluble circular disk 18'' which is also provided with a pattern or 100 scale consisting of holes and slots arranged symmetrically on both sides of a zero position marked by line I''.

In the first modification the row of selecting pins is arranged along a generating line 105 of the drum 18', while in the second modification it is arranged along a radius of the circular disk 18''. In the same way similar members transmit the vertical components of the stitches to a punching mechanism and 110 through it to the card, a corresponding perforation determining or punch selecting member being provided so as to move according to the components of the stitch 115 movements in the vertical component direction.

What I claim is:

1. In jacquard-card-punching machines, a 120 perforation determining or punch selecting arrangement comprising for the stitch transmission control in one component direction, a movable punch selecting member capable of being adjusted on either side of a zero position and having holes and slots constituting a pattern scale on both sides of a 125 zero line, means to operate said punch selecting member according to the stitch length to be transmitted in the respective component direction and an automatic returning mechanism arranged to restore the 130

punch selecting member at the end of every stitch movement, when this has operated a corresponding punch selection, positively back into its zero position.

5. 2. In jacquard-card-punching machines, a perforation determining or punch selecting arrangement comprising for the stitch transmission control in one component direction, a movable punch selecting slide capable of 10 being adjusted on either side of a zero position and having holes and slots constituting a pattern scale on both sides of a zero line, means to operate said punch selecting slide according to the stitch length to be transmitted 15 in the respective component direction and an automatic returning mechanism arranged to restore the punch selecting slide at the end of every stitch movement, when this has operated a corresponding punch selection, positively back into its zero position.

20 3. In jacquard-card-punching machines, a perforation determining or punch selecting arrangement comprising for the stitch transmission control in one component direction, a movable punch selecting member capable of 25 being adjusted on either side of a zero position and having holes and slots constituting

a pattern scale on both sides of a zero line, means to operate said punch selecting member according to the stitch length to be transmitted in the respective component direction, means for locking the punch selecting member in its adjusted position, a row of 30 selecting pins arranged above the punch selecting member and adapted to enter respectively the holes and slots thereof brought below them, means for temporarily moving said pin row up and down, means for temporarily disconnecting the punch selecting member from its operating means, a nipper 35 device adapted to return, when being closed, the punch selecting member, positively into its exact zero position, and means for temporarily operating said nipper device to close it and to thus effect the returning of 40 the punch selecting member.

In witness whereof I have hereunto signed my name this 21st day of February 1910, in the presence of two subscribing witnesses.

ROBERT ZAHN.
